UNITED STATES PATENT OFFICE.

WILLIAM L. POEHLMANN, OF PHILADELPHIA, PENNSYLVANIA.

HOLDER FOR PLACARDS, SIGNS, &c.

SPECIFICATION forming part of Letters Patent No. 640,943, dated January 9, 1900.

Application filed May 31, 1899. Serial No. 718,823. (No model.)

To all whom it may concern:

Be it known that I, WILLIAM L. POEHLMANN, a citizen of the United States, residing in the city and county of Philadelphia, State 5 of Pennsylvania, have invented a new and useful Improvement in Holders for Placards, Signs, &c., which improvement is fully set forth in the following specification and accompanying drawings.

10 My invention consists of a holder for a placard, sign, &c., embodying a head, a resilient standard, and means for clamping said standard to a basket or other receptacle, said parts being constructed as hereinafter described, and the novel features pointed out in the claim.

Figure 1 represents a perspective view of a holder embodying my invention. Fig. 2 represents a vertical section thereof on an enlarged scale. Fig. 3 represents a vertical section thereof.

Similar letters of reference indicate corresponding parts in the figures.

Referring to the drawings, A designates a head formed of a plate of metal or other suitable material and having in the front face thereof the parallel grooved bars B, between which are fitted the placards or indicators C of prices and quantities or names and other 25 information, as a sign. Riveted or otherwise secured to said head A, on the back thereof, is the plate D, to which is attached the bearing-piece E, somewhat like a staple, for the eye F of the standard G, by which latter said head is pivotally supported, said standard 30 consisting of the legs H H, which are joined by the eye F at the top thereof, so that they are resilient in their nature and adapted to spring apart and flare, as shown in Fig. 2.

40 On the legs is the sliding ring J, which is adapted to close the same, as shown in Figs. 1 and 3, it being noticed that when the ring is moved upwardly the legs flare at the lower portions and separate, when they may be placed on the wall of a basket or other receptacle so as to straddle the same, after which the ring is lowered, when the legs are pressed firmly against said wall, thus tightly clamping the holder to the receptacle.

The lower ends of the legs have inturned 50 shoulders K, so that when the holder is applied to a receptacle, such as a basket, with handle-openings L therein, said shoulders enter said openings, whereby the legs may come more closely together and firmly embrace the top rim of said basket. (See Fig. 1.) When no such openings exist, the shoulders may close against the wall of the basket, when, in order to prevent cutting of the basket by said shoulders, the latter have 60 tongues M depending therefrom, the same resting flat against said wall, as shown in Fig. 3. It will also be seen that the tongues M may be brought closely together and so held by means of the ring J, when they may 65 be inserted as one into an opening in the basket limited in descent by the shoulders K, which also serve to support the holder.

It will be seen that the matter on the head A is nicely presented to view, and said head 70 rests against the standard without liability to overturn, as the bearing E for the eye F is above the center of the head; but when the basket is overfull the head may be turned inwardly from below, so as to overhang the 75 contents of the basket and prevent its matter from being obscured or covered, as will be apparent in Fig. 3.

Having thus described my invention, what I claim as new, and desire to secure by Letters 80 Patent, is—

1. A holding-plate provided on its rear with a bearing-piece, in combination with resilient legs which are united at top by an eye integral therewith and mounted on said piece and 85 provided with an embracing closing-ring, the lower ends of said legs having inturned shoulders and tongues which depend from the inner ends of said shoulders.

2. Resilient legs joined at top by an eye, 90 and provided with an embracing closing-ring, in combination with a plate having on its rear, a bearing-piece on which said eye is mounted and on its face with means for holding a placard, &c., the lower portions of said 95 legs being flaring and provided with inturned shoulders.

3. Resilient legs joined at top by an eye and

provided with an embracing closing-ring, a plate having on its rear, a bearing-piece on which said legs are mounted by said eye, and on its face, parallel grooved bars, the lower ends of said legs having inturned shoulders and tongues depending from the inner ends of said shoulders, said parts being combined

forming an improvement in holders of the character stated.

WILLIAM L. POEHLMANN.
